UNITED STATES PATENT OFFICE.

JOHN H. WOOTTON, OF NEW YORK, N. Y.

SIGNALING SYSTEM.

Application filed September 7, 1922. Serial No. 588,736.

To all whom it may concern:

Be it known that I, JOHN H. WOOTTON, a citizen of the United States, residing in the borough of Manhattan, in the city, 5 county, and State of New York, have invented certain new and useful Improvements in Signaling Systems, of which the following is a specification.

This invention relates to signaling systems comprising a plurality of signal initiating stations and signal responsive devices and is particularly adapted for emergency signaling systems (such, for example, as automatic fire alarm systems which are intended for response to the closure of the 10 normally open contacts of thermostatic devices, or the like) in which all current carrying parts should be under constant test, in which it is desirable to minimize the 15 normal test current, and in which a current greatly in excess of the normal test current should be available for active signaling.

An object of this invention is to provide a system of the character described in 25 which all current carrying parts will be under constant test.

Another object is to provide construction and arrangement of parts whereby a single current source may be utilized for maintaining a normal test current; for energizing 30 the tripping magnets of annunciator units in response to the operation of circuit adjusters, groups of which may be associated respectively therewith; and for manifesting 35 warning signals at manifesting stations responsive to the operation of such circuit adjusters, which manifesting stations may be located in close proximity to or scattered 40 at considerable distances from such annunciator units.

Other objects and aims of this invention, more or less specific than those just referred to, will be in part obvious and in part pointed out in the course of the following description.

For the purpose of enabling this invention to be more readily understood, a typical illustrative embodiment thereof is shown in the annexed drawing and hereinafter described in detail, but this invention is not limited to such embodiment, as many changes may be made in construction and arrangement, and parts may be added or omitted without departing from the spirit 55 of this invention.

Like reference characters denote similar

parts throughout the accompanying drawings, in which—

Figure 1 diagrammatically illustrates a typical signaling system embodying this invention, and

Fig. 2 is a simplified schematic representation of the circuit arrangement of Fig. 1.

The signaling system illustrated by Fig. 1 comprises a plurality of circuit controllers 65 arranged in five groups generally designated as A, B, C, D and E, which are respectively associated with the annunciator units a, b, c, d and e; which annunciator units, together with the alarm devices R connected 70 in the alarm groups F and G, and the alarm loop controlling contactor H, constitute alarm manifesting mechanisms, while the trouble bell J, its controlling relay K, and the associated ammeter L comprise supervisory 75 manifesting mechanism.

The current supply for the entire system (with the exception of the local circuit for the trouble bell J) is provided by the current source P; and a system of conductors 80 is provided, which system is so arranged that a normal current path is provided from said source P, which path includes the windings and contacts of all of said devices, excepting only, as already stated, the local 85 current path of the trouble bell J. The four-pole double-throw switches, generally indicated by the reference letter Q, are individually associated with respective ones of the circuit controller groups A, B, C, D 90 and E; so that in the event of the development of a break or other fault in the conductors connecting any one of said groups of circuit controllers, the switch for such group may be reversed, thereby isolating 95 the conductors of such group from the remainder of the system, and establishing connections whereby the remainder of the system may function in the intended manner while such group of circuit controllers are 100 so disconnected therefrom.

Each of the circuit controllers of the groups A, B, C, D and E comprises the normally open closable contacts 21 and 22; and said controllers may consist of any 105 wellknown form of thermostatic or other device having contacts which are normally disconnected but which can be brought into engagement, in any desired manner, one with the other, for the purpose of causing 110 desired signal manifestations.

The annunciator units a, b, c, d and e

each comprise an electromagnet having the differential windings 23 and 24, an armature 25 one end of which is pivoted to the pole piece 26 and the other end of which is disposed adjacent the pole piece 27, and a retractile spring 28 so applied to the armature 25 as to tend to move the free end of said armature away from the pole piece 27 and to bring said armature into engagement with the stop 29. A gravity shutter 30 is hinged at 31 and is arranged so that, when said shutter is in its normal position, it may be engaged by the armature 25, if retracted, to hold said shutter against movement to its abnormal position; and so that, when said armature is in its attracted position, said shutter will be free to move from its normal to its abnormal position.

The contactor H comprises an electromagnet 32, its armature 33, and a contact member 34 carried by and insulated from said armature. The abutment 35 is situated in the path of the member 34, so as to furnish a backstop for limiting the retractive movement of the armature 33; and the contact 36 is mounted in the path of the attractive movement of said armature, and the contact 37 in that of the member 34, to the end that, when said armature 33 is in its attracted position, said armature and member will be in contact with said contacts 36 and 37, respectively.

The relay K comprises a high resistance electromagnet 40, its armature 41, and the backstop contact 42; said armature 41 being connected by the conductor 43 with one terminal of the battery 44; the other terminal of said battery being connected through the conductor 45, the bell J and the conductor 46 to the back stop 42. It will therefore be evident that so long as the electromagnet 40 is effectively energized, the armature 41 will remain in attracted position and the current path through the bell J will be interrupted; and that, when said electromagnet is not effectively energized, said armature 41 will move to its retracted position, thereby establishing a connection with the back stop 42 and closing a current path from the battery 44 through the bell J, so as to cause said bell to sound, for a purpose which will be hereinafter more fully explained.

The alarm devices R, diagrammatically represented as typical bells, may consist of any desired form of signal manifesters; such devices being so constructed and arranged that they will not act in response to either making or breaking of current flow in the circuit in which they are included, unless such current flow equals a certain predetermined intensity; and so that such devices will cause a desired signal manifestation in response to current flow in the circuit in which they are connected, equaling or exceeding such predetermined intensity.

Each of the switches Q comprises the hinged blades 51, 52, 53 and 54, the free ends of which blades are secured to the insulating yoke 55; to which yoke the operating handle 56 is attached. The blades 51, 52, 53 and 54 normally engage the jaws 57, 58, 59 and 60, respectively; but upon reversal of such blades they may be brought into engagement with the jaws 61, 62, 63 and 64, respectively; the jaw 61 being permanently connected to the jaw 64 by means of the conductor 65 and the jaws 62 and 63 being permanently connected by the conductor 66.

The normal current path from the source P is as follows: from one terminal of said source, through conductor 101, and armature 33 of contactor H, to one end of the winding of the electromagnet 32 of said contactor; thence through said winding and through conductor 103 to one end of the winding 23 of the annunciator unit a; thence through said winding, through conductor 104, blade 51 and jaw 57 of the switch Q associated with group A of the circuit controllers, through conductor 105, through either the contact 21 or the contact 22 of each of the circuit controllers of group A, through jaw 60 and blade 54 of said switch Q, and through conductor 106 to one terminal of the differential winding 24 of the annunciator unit a; thence through such winding of said unit in such direction as to counteract the effect of winding 23, through conductor 107, through the blade 52 and jaw 58 of the switch Q associated with group B of said circuit controllers, through conductor 108 and through either the contact 21 or the contact 22 of each of the circuit controllers of said group B, through jaw 59 and blade 53 of said switch Q, and through conductor 109 to one terminal of the winding 23 of the annunciator unit c; thence through said winding and through conductor 110, through the switch Q associated with group C of circuit controllers, and through the conductor 105 and the contacts of said controllers as in the case of group A, through conductor 111 and winding 24 of said annunciator unit c as in annunciator unit a, already described; thence through conductor 112, the switch Q, conductor 108 and contacts of circuit controllers of group D in a manner corresponding to that of group B as hereinbefore described, and through conductor 113 to one terminal of the winding 23 of annunciator unit e; thence through said winding, through conductor 114, through switch Q, conductor 105 and contacts of circuit controllers of group E, as in group A hereinbefore described, through conductor 115 to and through winding 24 of annunciator unit e, as in annunciator unit a hereinbefore described; thence through conductor 116 to one end of the winding of the electromagnet 40 of the relay K, through

said winding, through the conductor 117, through the ammeter L and through conductor 118 to and through the switch Q, conductor 108 and contacts of circuit controllers of group A, as through group B hereinbefore described; thence through conductor 119, through the differential windings of the annunciator unit b, through conductor 120, the switch Q, conductor 105, contacts of circuit controllers of group B and conductor 121, in a manner corresponding to that hereinbefore described in detail for the first current path through annunciator unit a and group A; thence through conductor 122, switch Q, conductor 108 and contacts of circuit controllers of group C in a manner corresponding to that hereinbefore described in detail for the first currents path through group B; thence through conductor 123, the windings of annunciator unit d, through conductor 124, the switch Q, conductor 105, contacts of circuit controllers of group D and conductor 125, in a manner corresponding to that hereinbefore described in detail for the first current path through annunciator unit a and group A; thence through conductor 126, switch Q, conductor 108, contacts of circuit controllers of group E in a manner corresponding to that hereinbefore described in detail for the first current path through group B; thence through conductor 127 to contact member 34 of contactor H, through said member and through conductor 128, through the devices R serially included therein, to contact 36 of said contactor; thence through said contact and correspondingly through conductor 129 and the devices R of group G to contact 37 of said contactor; thence through said contact and through conductor 130, to the other terminal of the current source P.

From the foregoing it will be seen that, under normal conditions, a test current path is maintained through each of the contacts of each of the circuit controllers of the groups A, B, C, D and E; through each of the windings of the annunciator units a, b, c, d and e; through the electromagnet windings of the relay K; through the ammeter L; through all of the alarm devices R and through all of the current carrying parts of the contactor H.

The resistance of the winding of the electromagnet 40 of the relay K is so high that when the normal current path is established therethrough, as just described, the intensity of the current flow from the source P therethrough will be insufficient to cause responsive action of the devices R, and will constitute an extremely small drain upon the capacity of the source P; the said relay K being so adjusted that in the event of the interruption of the normal current path just described, or of such diminution of current flow therethrough as would occur in the

event that the electromotive force of said current source was diminished to a point insufficient to cause intended operation of the annunciator units, contactor and alarm devices (as hereinafter more fully explained), the armature 41 of said relay will move to retracted position, and thereby cause a warning signal to be sounded by the bell J.

As hereinbefore stated, the normal current path through the differential windings of the annunciator units a, b, c, d and e is so arranged that one of said windings neutralizes the other in each of said units; and said units may be so arranged as to be unresponsive to normal test current flow through one of the windings thereof, even in the absence of opposing energization of the other winding thereof; but such annunciator units should be so arranged that in the event of current flow through one of the windings thereof in predetermined excess of that through the other winding, the armature 25 of such unit will be moved to attracted position and the shutter 30 will thereupon drop to indicating position.

The contactor H is so arranged that current flow therethrough of such intensity as occurs from the source P through the normal current path hereinbefore described in detail will not cause effective energization of the electromagnet 32 of such contactor, and so that current flow through said magnet of predetermined excess above such normal flow will cause sufficient energization of the magnet 32 to cause the armature 33 to move into engagement with the contact 36, and thereby carry the member 34 into engagement with the contact 37.

As most clearly shown by Fig. 2, this system comprises a signal circuit having two parallel loops, one end of one of which loops is connected with the opposite end of the other of said loops through the supervisory signal manifesting means comprising the high resistance relay K and the meter L; the current source P and alarm mechanism comprising the contactor H and the devices R being connected between the remaining ends of said loops.

In detail, one of said parallel loops comprises, in the order stated, the conductor 103, the winding 23 of the annunciator unit a, conductor 104, the blade 51 and jaw 57 of the switch Q associated with group A, conductor 105 and either the contact 21 or the contact 22 of each of the circuit controllers of said group, the jaw 60 and blade 54 of said switch, the conductor 106, winding 24 of the annunciator unit a, conductor 107, the blade 52 and jaw 58 of the switch Q associated with group B, conductor 108 and either the contact 21 or the contact 22 of each of the circuit controllers of said group, the jaw 59 and blade 53 of said last named switch Q, conductor 109, winding 23 of an-

nunciator unit *e*, conductor 110; the blade 51 and jaw 57 of the switch *Q* associated with group *C*, conductor 105 and either the contact 21 or the contact 22 of each of the 5 circuit controllers of said group, the jaw 60 and blade 54 of said last named switch *Q*, conductor 111, winding 24 of annunciator unit *e*, conductor 112, blade 52 and jaw 58 of switch *Q* associated with group *D*, conductor 108 and either the contact 21 or the contact 22 of each of the circuit controllers of said group, jaw 59 and blade 53 of 10 said last named switch *Q*, conductor 113, winding 23 of annunciator unit *e*, conductor 114, blade 51 and jaw 57 of the switch *Q* associated with group *E*, conductor 105 and either the contact 21 or the contact 22 of each of the circuit controllers of said group, jaw 60 and blade 54 of said last named 15 switch *Q*, conductor 115, winding 24 of annunciator unit *e*, and conductor 116.

The other of said parallel loops leads to 20 said groups of circuit controllers in reverse order and includes the windings of the annunciator units which are not included in said first named group; and said other loop comprises, in the order stated, conductor 127, the blade 53 and jaw 59 of the switch *Q* associated with group *E*, conductor 108 and 25 the contacts of the circuit controllers of such group which were not serially included in the first described loop, the jaw 58 and blade 52 of said switch, conductor 126, winding 24 of annunciator unit *d*, conductor 125, 30 blade 54 and jaw 60 of the switch *Q* associated with group *D*, conductor 105 and the contacts of the circuit controllers of such group which were not serially included in the first described loop, jaw 57 and blade 51 35 of said last named switch *Q*, conductor 124, winding 23 of annunciator unit *d*, conductor 123, blade 53 and jaw 59 of the switch *Q* associated with group *C*, conductor 108 and the contacts of the circuit controllers 40 of such group which were not serially included in the first described loop, jaw 58 and blade 52 of said last named switch *Q*, conductor 122, winding 24 of annunciator unit *b*, conductor 121, blade 54 and jaw 60 45 of the switch *Q* associated with group *B*, conductor 105 and the contacts of the circuit controllers of such group which were not serially included in the first described loop, jaw 57 and blade 51 of said last named 50 switch *Q*, conductor 120, winding 23 of annunciator unit *b*, conductor 119, blade 53 and jaw 59 of the switch *Q* associated with group *A*, conductor 108 and the contacts of the circuit controllers of such group which 55 were not serially included in the first described loop, jaw 58 and blade 52 of said last named switch *Q*, and conductor 118.

By virtue of the novel signal circuit arrangement hereinbefore described in detail, it will be seen that closure of the contacts

of any controller will establish a current path from the source *P* including one of the differential magnet windings of the associated annunciator unit, the windings of the alarm mechanisms *H* and *R* and the 70 windings of alternate ones of the remaining annunciator units. As such current path excludes the windings of every alternate annunciator unit, the current flow therethrough will be at least double that 75 through the normal current path hereinbefore described in detail; and because such current path also excludes the high resistance relay *K*, the current flow therethrough will be still further augmented. 80

In the use of the signaling system shown by the drawings, all parts are normally positioned as shown, and the normal test or supervisory current path is as hereinbefore described in detail; the bell *J* and devices *R* 85 being inactive because the energization of magnet 40 of relay *K* causes interruption of the current path through said bell *J*, and because the test current path effective through said devices *R* includes the two 90 parallel loops hereinbefore described in detail and the high resistance relay *K* and meter *L*. The high resistance of the current path thus normally effective minimizes the drain upon the current source *P* so that 95 battery cells may be employed for such source and a long service life secured therefrom.

In the event that a connection is established between the contacts of any one of the 100 circuit controllers, the shutter of the annunciator unit associated with the group of which such controller forms part will move to indicating position, the electromagnet of the contactor *H* will be effectively energized 105 and the armature of said contactor will thereupon move to attracted position, and the devices *R* of groups *F* and *G* will thereupon be connected in parallel across the terminals of the current source *P*, so that said 110 devices will give intended warning of the closure of such contacts. The closure of the contacts of any circuit controller, as just described, will terminate the effective energization of the magnet 40 of relay *K*, and 115 the armature 41 of said relay will thereupon move to retracted position, thereby causing the bell *J* to sound. Thereafter, upon separation of the contacts of such active circuit controller, or, in the absence of 120 such separation, upon reversal of the switch *Q* associated with the group of which such circuit controller forms part, the relay *K* and contactor *H* will be restored to their respective normal conditions, and thereupon 125 the activity of the bell *J* and the devices *R* will cease.

Assuming, for example, that a connection is established between the contacts 21 and 22 of one of the circuit controllers of group *A*, 130

- a current path will be established from one terminal of the source P, through conductor 101, armature 33 and winding 32 of contactor H, conductor 103, winding 23 of annunciator unit a, conductor 104, blade 51 and jaw 57 of switch Q associated with group A, conductor 105 and the closed contacts of the active controller, conductor 108, jaw 59 and blade 53 of said switch Q, conductor 119, winding 23 of annunciator unit b, conductor 120, blade 51 and jaw 57 of the switch Q associated with group B, conductor 105 and either the contact 21 or the contact 22 of each of the circuit controllers of said group, jaw 60 and blade 54 of said last named switch Q, conductor 121, winding 24 of annunciator unit b, conductor 122, blade 52 and jaw 58 of switch Q associated with group C, conductor 108 and either the contact 21 or contact 22 of each of the circuit controllers of said group, jaw 59 and blade 53 of said last named switch Q, conductor 123, winding 23 of annunciator unit d, conductor 124, blade 51 and jaw 57 of the switch Q associated with group D, conductor 105 and either the contact 21 or the contact 22 of each of the circuit controllers of said group, jaw 60 and blade 54 of said last named switch Q, conductor 125, winding 24 of annunciator unit d, conductor 126, blade 52 and jaw 58 of the switch Q associated with group E, conductor 108, and either the contact 21 or contact 22 of each of the circuit controllers associated with said group, jaw 59 and blade 53 of said last named switch Q, conductor 127, member 34 of contactor H, conductor 128 and devices R of group F, contact 36 of contactor H, conductor 129 and devices R of group G, contact 37 of contactor H, and conductor 130, to the other terminal of source P.
- Upon the establishment of the current path just described, the electromagnet 32 of the contactor H will be effectively energized, the armature 33 will thereupon move to attracted position; thus establishing three parallel current paths across the terminals of the current source P. One of said three current paths will constitute the signaling circuit current path comprising the conductor 101, armature 33 and winding of the electromagnet 32 of the contactor H and the conductor 103, thence through the signaling circuit current path hereinbefore just described in detail to and through conductor 127, thence through member 34 and contact 37 of contactor H, and conductor 130. Another of said three current paths will constitute the current path through the devices R of group F, comprising the conductor 101, armature 33 and contact 36 of the contactor H, the conductor 128, and devices R serially included therein, the member 34 and contact 37 of said contactor, and the conductor 130. The other of said current paths will consti-
- tute the current path through the devices R of group G, comprising the conductor 101, armature 33 and contact 36 of the contactor H, the conductor 129 and devices R serially connected therein, the contact 37 of said contactor, and the conductor 130. When the three current paths have been established, as just described, the electromagnet of the annunciator unit a will be effectively energized, its armature 25 will be in attracted position, and its shutter 30 will be in indicating position; and the devices R of groups F and G will give the intended alarm manifestation.
- Should circuit controllers of two or more groups close simultaneously or concurrently, annunciator units associated with such groups will act in a predetermined manner, which will be best understood by a perusal of the following examples: If connections are established between the contacts of circuit controllers of groups A and B, winding 23 of annunciator unit a will have full alarm current energization and winding 24 of said unit will have one-half such energization, the winding 24 of unit b will have full alarm current energization and the winding 23 of said unit will have one-half said energization; the windings of units c and e will have a mere nominal energization, while the windings of unit d will have full alarm current energization. Inasmuch as the current so transverses the differential windings of units c, d and e as to cause such windings to act in opposition one to the other, the magnets of said units will not be effectively energized, but the magnets of units a and b will be effectively energized, and their shutters 30 will therefore move to indicating position. If connections are established between contacts of circuit controllers in groups A and C, the annunciator units a and c will correspondingly act in response thereto.
- If contacts of circuit controllers in three or more groups close simultaneously, the annunciators of the first and last of such groups (in the order in which they are connected in the alarm circuit loops) will respond to such closures. For example, if connections are simultaneously established between contacts of circuit controllers in groups A, B and C, annunciator units a and c will respond.
- In this connection it is pointed out that, as is well understood by those skilled in this art, it would be very unusual for contacts of circuit controllers in two groups to close simultaneously, and the chances are extremely remote of contacts closing simultaneously in three or more groups. For these reasons, it may be assumed that if connections are concurrently established between the contacts of circuit controllers in several groups, such connections will be established one after another so that the first to be estab-

lished will cause responsive action of its associated annunciator unit.

It is ordinarily deemed preferable that all annunciator units shall not act in response to the closure of contacts of circuit controllers in all or a considerable number of groups; but, rather, that such annunciator units shall indicate the start and end of the series of groups having active circuit controllers. For example, assuming that the circuit controllers of groups A, B, C, D and E are distributed upon the fifth, fourth, third, second and first stories of a building, respectively, and that such controllers are operable as fire detecting thermostats,—should a fire occur in the first story, contacts of one or more circuit controllers in group E would close, thereby sounding an alarm and causing the annunciator unit *e* to act to show that the fire was on the first floor; while, should there be a "flash fire" involving the first, second and third floors,—the alarm would sound and (assuming that contacts of the circuit controllers of all three floors closed simultaneously) annunciator units *c* and *e* would act, thus indicating that the area of the building from the first to the third floors, inclusive, was involved.

In the event of failure or operative impairment of the connection between either the contact 21 or the contact 22 of any circuit controller and its associated conductor 105 or 108 (as the case may be), or of the electrical connection between any one of the alarm devices R and its associated conductor, current flow through the test current path hereinbefore described in detail would be thereby interrupted or substantially decreased, whereupon the electromagnet 40% of the relay K would no longer sustain the armature 41, and said armature would move into engagement with the back-stop 42, and thereby complete the circuit through the trouble bell J.

It will be evident to those skilled in this art that the use of the meter L is optional, and that the relay K may be omitted, if it is not desired to provide a supervisory trouble signal such as that shown. In the event of the omission of both the relay K and the meter L, the conductors 116 and 118 may be directly joined; although it will usually be found desirable to provide a high resistance connection between such conductors, in order to suitably minimize the drain upon the current source P. Even if the conductors 116 and 118 are joined without the use of a resistance therebetween, the annunciators and alarm devices will operate in the desired manner, responsive to closure between the contacts of any of the circuit controllers, so long as the magnet windings of succeeding annunciator units are connected, as described, in alternate ones of the two parallel signal circuit loops.

It will also be evident that other changes may be made in the construction and arrangement of the system shown by the accompanying drawings and hereinbefore described, without departing from the spirit 70 of this invention.

What I therefore claim and desire to secure by Letters Patent of the United States of America is:

1. In a signaling system, a signal circuit comprising two parallel loops, a high resistance connection between one end of one of said loops and the opposite end of the other thereof, signal manifesting means arranged for response to variations of current flow through said connection, a current source and signal manifesting means connected between the remaining ends of said loops, signal devices each having a differentially wound electromagnet, magnet windings of succeeding devices connected in alternate ones of said loops, and circuit controllers each having normally open closable contacts serially connected in one and the other of said loops, respectively, at adjacent portions thereof, one of the contacts of each controller connected in a portion of one or the other of said loops which is situated between the differential magnet windings of one or another of said signal devices. 95

2. In a signaling system, a signal circuit comprising two parallel loops, a high resistance connection between one end of one of said loops and the opposite end of the other thereof, signal manifesting means arranged for response to variations of current flow through said connection, a current source connected between the remaining ends of said loops, signal devices each having a differentially wound electromagnet, magnet windings of succeeding devices connected in alternate ones of said loops, and circuit controllers each having normally open closable contacts serially connected in one and the other of said loops, respectively, at adjacent portions thereof, one of the contacts of each controller connected in a portion of one or the other of said loops which is situated between the differential magnet windings of one or another of said signal devices. 100

3. In a signaling system, a signal circuit comprising two parallel loops, signal manifesting means connected between one of said loops and the opposite end of the other thereof, a current source and signal manifesting means connected between the remaining ends of said loops, signal devices each having a differentially wound electromagnet, magnet windings of succeeding devices connected in alternate ones of said loops, and circuit controllers each having normally open closable contacts serially connected in one and the other of said loops, respectively, at adjacent portions thereof, one of the contacts of each controller connected in a portion of one or the other of said loops which is situated between the differential magnet windings of one or another of said signal devices. 115

contacts of each controller connected in a portion of one or the other of said loops which is situated between the differential magnet windings of one or another of said signal devices.

4. In a signaling system, a signal circuit comprising two parallel loops, signal manifesting means connected between one end of one of said loops and the opposite end of the other thereof, a current source connected between the remaining ends of said loops, signal devices each having a differentially wound electromagnet, magnet windings of succeeding devices connected in alternate ones of said loops, signal devices connected in a portion of one or the other thereof, a current source connected between the remaining ends of said loops, signal devices each having a differentially wound electromagnet, magnet windings of succeeding devices connected in alternate ones of said loops, and circuit controllers each having normally open closable contacts serially connected in one and the other of said loops, respectively, at adjacent portions thereof, one of the contacts of each controller connected in a portion of one or the other of said loops which is situated between the differential magnet windings of one or another of said signal devices.

5. In a signaling system, a signal circuit comprising two parallel loops, a high resistance connection between one end of one of said loops and the opposite end of the other thereof, a current source and signal manifesting means connected between the remaining ends of said loops, signal devices each having a differentially wound electromagnet, magnet windings of succeeding devices connected in alternate ones of said loops, circuit controllers each having normally open closable contacts serially connected in one and the other of said loops, respectively, at adjacent portions thereof, one of the contacts of each controller connected in a portion of one or the other of said loops which is situated between the differential magnet windings of one or another of said signal devices.

6. In a signaling system, a signal circuit comprising two parallel loops, one end of one of which is connected to the opposite end of the other thereof, a current source and signal manifesting means connected between the remaining ends of said loops, signal devices each having a differentially wound electromagnet, magnet windings of succeeding devices connected in alternate ones of said loops, and circuit controllers each having normally open closable contacts serially connected in one and the other of said loops, respectively, at adjacent portions thereof, one of the contacts of each controller connected in a portion of one or the other of said loops which is situated between the differential magnet windings of one or another of said signal devices.

7. In a signaling system, a signal circuit comprising two parallel loops, a high resistance connection between one end of said loops and the opposite end of the other thereof, a current source connected between

the remaining ends of said loops, signal devices each having a differentially wound electromagnet, magnet windings of succeeding devices connected in alternate ones of said loops, and circuit controllers each having normally open closable contacts serially connected in one and the other of said loops, respectively, at adjacent portions thereof, one of the contacts of each controller connected in a portion of one or the other of said loops which is situated between the differential magnet windings of one or another of said signal devices.

8. In a signaling system, a signal circuit comprising two parallel loops one end of one of which is connected to the opposite end of the other thereof, a current source connected between the remaining ends of said loops, signal devices each having a differentially wound electromagnet, magnet windings of succeeding devices connected in alternate ones of said loops, and circuit controllers each having normally open closable contacts serially connected in one and the other of said loops, respectively, at adjacent portions thereof, one of the contacts of each controller connected in a portion of one or the other of said loops which is situated between the differential magnet windings of one or another of said signal devices.

9. In a signaling system, a signal circuit comprising two parallel loops one end of one of which is connected to the opposite end of the other thereof, a current source connected between the remaining ends of said loops, signal devices each having a differentially wound electromagnet, magnet windings of succeeding devices connected in alternate ones of said loops, means associated with respective ones of said devices for causing effective energization of the differentially wound magnet thereof by establishing a connection from the portion of one of said loops which is situated between the differential magnet windings of such associated device and the other of said loops.

10. In a signaling system, groups of circuit controllers each controller having a normally open closable contact, a signal device associated with each group having a differentially wound electromagnet, an alarm mechanism comprising a controlling electromagnet, a resistance for suitably limiting the normal current flow, a current source, and a system of conductors so arranged that a normal current path will be provided from said source, which path will include all of said contacts and windings and said resistance, and so that closure of the contact of any controller will establish a current path from said source including one of the differential magnet windings of the signal device associated with such controller signal devices and also the windings of said alarm mechanism and the windings of the alter-

nate ones of the others of said signal devices and excluding said resistance and the windings of the remainder of said devices.

11. In a signaling system, groups of circuit controllers each controller having a normally open closable contact, a signal device associated with each group having a differentially wound electromagnet, alarm and supervisory manifesting mechanisms each comprising a controlling electromagnet, a current source, and a system of conductors so arranged that a normal current path will be provided from said source which path will include all of said contacts and windings,

and so that closure of the contacts of any 15 controller will establish a current path from said source including one of the differential magnet windings of the signal device associated with such controller and also the windings of said alarm mechanism and the 20 windings of the alternate ones of the other of said signal devices and excluding the windings of the remainder of said devices and of said supervisory mechanism.

In witness whereof, I hereunto subscribe 25 my name this 29th day of August, 1922.

JOHN H. WOOTTON.
